(57) **CLAIM**

The ornamental design for a spinal distraction structure, as
shown and described.

DESCRIPTION

FIG. 1 is a bird's-eye isometric view showing the front, top,
and side of my new ornamental design for a spinal distraction
structure;

FIG. 2 is a top plan view of the spinal distraction structure
shown in FIG. 1;

FIG. 3 is a side elevational view of the spinal distraction
structure shown in FIG. 1, the opposite side of which is a
mirror image;

FIG. 4 is a front elevational view of the spinal distraction
structure shown in FIG. 1; and,

FIG. 5 is a rear elevational view of the spinal distraction
structure shown in FIG. 1.

The broken lines shown are for illustrative purposes only and
form no part of the claimed design.
